UNITED STATES PATENT OFFICE.

CYRENUS W. LENT, OF BYRON, CALIFORNIA.

SMOKE-PRECIPITATOR.

1,103,304.

Specification of Letters Patent. Patented July 14, 1914.

Application filed May 26, 1913. Serial No. 769,838.

To all whom it may concern:

Be it known that I, CYRENUS W. LENT, a citizen of the United States, residing at Byron, in the county of Contra Costa and State of California, have invented a new and useful Smoke-Precipitator, of which the following is a specification in such full and clear terms as will enable those skilled in the art to construct and use the same.

10 This invention relates to an apparatus for the precipitation of the solid or soluble particles from smoke.

15 It will be understood by those skilled in the art that in the operation of boilers and other industrial furnaces that great quantities of smoke are frequently emitted therefrom. This smoke often contains minute particles of carbon, sulfurous dioxid and other impurities, which are often the cause 20 of litigation and complaint upon the part of persons in the vicinity of the furnace and often cause disturbance for miles therefrom.

25 While in the present case the invention has been illustrated as applied to an ordinary form of upright boiler, it will be apparent to those skilled in the art that it may be applied equally well to any furnace having a smoke stack extending therefrom.

30 Another object of the invention is to provide an apparatus which is capable of collecting solids precipitated in order to permit the recovery therefrom of a useful product, as in the case of lamp smoke or quicksilver 25 fumes.

Other objects will appear as the description proceeds.

35 An embodiment of the invention is shown in the drawings in which the same reference numeral is applied to the same portion throughout, but I am aware that there are many modifications thereof.

Figure 1 is a view in side elevation partly in section of the complete apparatus, Fig. 2 40 is a side elevation of one of the wheels used for breaking up the water stream and causing a more intimate mixture therewith of the smoke, Fig. 3 is a portion of one of the wheels and the bearing thereof used for 45 breaking up the water stream, Fig. 4 is a view of the pump and smoke precipitating chambers at right angles to Fig. 1, and Fig. 5 is a view of the boiler taken on the line 50 5-5. Fig. 1.

55 It will be understood by those skilled in the art that any suitable material may be

used for the construction of the smoke precipitating chambers, the kind of smoke being treated determining the character of material to be used, coal smoke requiring nothing more than a metallic precipitator while smoke containing much sulfur would require an insoluble tiling to prevent its rapid destruction. 60

The numeral 1 indicates an ordinary 65 boiler having a furnace door 2, gage 3 and smoke stack 4. The smoke stack is provided with a damper 5 operated by means of the handle 6 and it has a pipe 7 connected therewith, which pipe extends to the smoke 70 precipitating chambers. The pipe 7 is connected with the top of the smoke precipitating chamber 8, said chamber being of suitable size to permit the passage therethrough of the quantity of smoke discharged from 75 the furnace.

A steam pipe 9 is connected with the boiler and connects in turn with pipes 10 and 11. The pipe 10 extends upwardly and is connected with the top of the smoke 80 precipitating chamber 8, a valve 12 enabling the quantity of steam discharged therefrom to be regulated at will. Within the smoke precipitating chamber 8 there are a number of inclined baffle plates 13, said plates overlapping each other at their center in such a way as to cause the water discharged from one plate to fall upon the next plate below, thus making a practically continuous curtain of water through which the gases and 85 smoke must pass. A pipe 14 connects the upper smoke precipitating chamber with the lower chamber 15. This lower chamber has a plurality of oppositely placed inclined 90 baffle plates 16, the edges of said plates being set to discharge upon the edges of the blades of a series of paddle wheels 17. 95

The paddle wheels 17 are each provided with four blades and are journaled in suitable bearings 18 outside of the casing 15, 100 said journal bearings being outside of the casing for the purpose of preventing the smoke and any gritty particles that might be therein from injuring said bearings. At the bottom the chamber 15 is provided with 105 the discharge pipe 19, said pipe being horizontal at 20 to connect with the sludge tank 21. The pipe 11 is connected with a horizontal pipe 22, which latter has a valve 23 while a pipe 24 is connected with said 110 valve and has a spray nozzle 25 thereon within the pipe 19. The spray nozzle is for

the purpose of causing the necessary downward draft through both of the smoke precipitating chambers and into the sludge tank.

5 The sludge tank 21 is of such depth and area as may be necessary to collect the solid particles from the given plant. It is provided with a discharge lip 26 and a water discharge pipe 27, the latter having an upwardly turned portion 28 and vent 29 to prevent the water from siphoning down below the opening 26. The water discharge pipe empties into a water tank 30 from which the water supply pipe 31 extends to a suitable 10 pump 32, said pump having a pipe 33 extending therefrom and discharging into the vertical pipe at the top of the first smoke precipitating chamber.

From the foregoing it will be clear that 20 in operation the fire is started in the boiler furnace, a damper in the smoke stack being left open until said fire raises sufficient steam to discharge the same into the top precipitating chamber and out the spray nozzle 25. The supply of steam let into the top precipitating chamber is for the purpose of humidifying the smoke to such an extent as may become necessary to cause either the solid or soluble particles therein 25 to be either precipitated in or dissolved by the water, while the spray nozzle 25 is for the purpose of humidifying the smoke and to create the necessary draft for the furnace, all excess gas passing off from the precipitating tank by way of the vent pipe 33'. After the boiler has got up steam, a certain amount is allowed to discharge into the upper smoke precipitating chamber and a sufficient amount to cause the necessary 30 draft is discharged from the spray nozzle 25, wheretupon the damper 5 may be closed and all of the smoke will be passed through the smoke precipitating chambers whereupon the pump may be started and will discharge water into the top of the upper smoke precipitating chamber, which water will pass therethrough from one baffle plate to the other in the form of a thin curtain which will compel the smoke to pass therethrough, and as the water passes down into the second smoke precipitating chamber it will discharge at the lower edges of the baffle plates 16 on to the blades of the wheels 17, causing the latter to beat up the particles 35 of water with the smoke, thus effectively precipitating the solid particles or dissolving soluble particles in the water, and as the mass of water and soluble particles pass downward it is discharged into the tank 21, 40 the solid particles collecting in the bottom thereof as sludge. Since more or less of the smoke particles will float upon the top of the water as a screen there is an opening in the side of the tank 21 adjacent the discharge lip 26 to permit this scum to be

raked off occasionally, while the bottom is inclined as shown at 34 and an inclined bottom pocket 35 is formed on one side of said tank to enable the attendant to readily remove the sludge from the bottom of said tank whenever necessary, the hole or pocket being used for this purpose.

70 It will be observed that the water is used over and over again so that if the smoke contains soluble particles or gases the solution will continually increase in strength from time to time. It will be observed that the pipe 27 discharges from an intermediate portion of the receptacle 21, the object being to prevent the scum from passing into the tank 30, while at the same time permitting ample depth of the tank to collect heavy sludge.

Having thus described my invention what I claim as new and desire to secure by Letters Patent of the United States, is as follows, modifications within the scope of the claims being expressly reserved:

1. An apparatus for the precipitation of smoke comprising in combination a steam generator, a furnace therefor, a flue extending away from said furnace, a smoke precipitating chamber having a plurality of baffle plates therein, means to deliver a stream of water upon said baffle plates, pipe connections to deliver steam into said chamber and to induce a gas current therethrough, a sludge tank into which the water, steam and smoke are discharged, and a pipe to discharge the water from said sludge tank to a tank from which the water is pumped to the smoke precipitation chamber, substantially as described.

2. In a smoke precipitation apparatus, the combination of a steam generator, a furnace, a flue leading from the furnace to a smoke precipitation chamber, a plurality of overlapping inclined baffle plates in said chamber, means to deliver a stream of water upon said baffle plates, a second smoke precipitation chamber with which the first chamber communicates, inclined baffle plates and revoluble wheels in said second chamber to mix the smoke and water passing therethrough, a sludge tank, pipe connections from the steam generator for supplying the first smoke precipitation chamber with steam and for inducing the movement of smoke through both of said precipitation chambers and into the sludge tank, and means to return the water from the sludge tank to the smoke precipitation chambers for reuse, substantially as described.

3. A smoke precipitation apparatus comprising the combination of a steam generator, a furnace, a flue leading from the furnace and connected with a smoke precipitation chamber, a plurality of overlapping baffle plates therein, a chamber adapted to deliver a stream of water into the top of

said smoke precipitation chamber, and upon said baffle plates, a second precipitation chamber having a plurality of inclined baffle plates therein, revoluble paddle wheels 5 under the lower edges of the baffle plates and in the second precipitation chamber and capable of being rotated by the water passing over the edges of said baffle plates, steam connections for supplying the smoke 10 precipitation chambers with steam for inducing the movement of smoke and gas therethrough, and a sludge tank into which the water and smoke are discharged, substantially as described.

15 4. In an apparatus for the precipitation of smoke, the combination of a steam generator, a furnace, a flue leading from said furnace, a smoke precipitation chamber with which said flue is connected, a plurality 20 of oppositely disposed, overlapping inclined baffle plates in said chamber, a pump for discharging water into the top of said

chamber and upon said baffle plates, a steam pipe for delivering steam into the top of said precipitation chamber, a second chamber connected with the first one and having a series of oppositely inclined baffle plates 25 therein, a plurality of paddle wheels in said second chamber, each adapted to be rotated by the water passing off the several baffle plates, a sludge tank, a pipe connecting the second smoke precipitation chamber with the sludge tank, and a steam spray nozzle in said pipe to induce the travel of smoke and gases through said chambers, substantially as described.

In testimony whereof I have hereunto set my hand this 19th day of May A. D. 1913, in the presence of the two subscribed witnesses.

C. W. LENT.
